UNITED STATES PATENT OFFICE

159,657

TOY ANIMAL FIGURE OR THE LIKE

Thomas C. Martin, Natick, Mass.

Application February 5, 1948, Serial No. 144,298

Term of patent 14 years

(Cl. D34--2)

To all whom it may concern:

Be it known that I, Thomas C. Martin, a citizen of the United States, residing in Natick in the county of Middlesex and State of Massachusetts, have invented a new, original, and ornamental Design for a Toy Animal Figure or the like, of which the following is a specification, reference being had to the accompanying drawing forming a part thereof, in which Fig. 1 shows a side view;

Fig. 2 shows a top plan view; and

Fig. 3 shows a front view of the toy animal figure or the like showing my new design.

I claim the ornamental design for a toy animal figure or the like, as shown.

THOMAS C. MARTIN.
